(57) **CLAIM**

The ornamental design for a cargo box, as shown and described.

DESCRIPTION

FIG. 1 is a right rear elevated perspective view of a cargo box showing our new design.

FIG. 2 is a plan view of the cargo box design of FIG. 1.

FIG. 3 is a front view of the cargo box design of FIG. 1.

FIG. 4 is a rear view of the cargo box design of FIG. 1.

FIG. 5 is a right side view of the cargo box design of FIG. 1; and,

FIG. 6 is a left side view of the cargo box design of FIG. 1.

The broken lines shown in FIGS. 1, 4, 5 and 6 are for illustrative purposes only and form no part of the claimed design.
